[57] **CLAIM**

The ornamental design for a shoe sole, as shown and described.

DESCRIPTION

FIG. 1 is a left side elevational view of a shoe sole showing my new design, the broken line showing of a shoe being environmental only and forming no part of the claimed design;

FIG. 2 is a bottom plan view thereof;

FIG. 3 is a right side elevational view thereof;

FIG. 4 is a front view thereof; and

FIG. 5 is a rear view thereof.

FIG. 1

FIG. 2

FIG. 3

FIG. 5

FIG. 4
